UNITED STATES PATENT OFFICE.

MARION ALLEN RADER, OF MEDFORD, OREGON.

DOOR-LATCH.

1,177,445.

Specification of Letters Patent. Patented Mar. 28, 1916.

Application filed June 16, 1915. Serial No. 34,435.

To all whom it may concern:

Be it known that I, MARION ALLEN RADER, a citizen of the United States, residing at Medford, in the county of Jackson and 5 State of Oregon, have invented a new and useful Door-Latch, of which the following is a specification.

The present invention appertains to latches, and has for its object the provision 10 of a door latch of novel and improved construction.

This invention resides in the provision of a latching device of unique construction, whereby the reciprocation of a spindle is 15 utilized for turning a latch bolt to one position or the other in order that it may be forced against its spring when the door is pulled or pushed open.

The invention embodies a latch bolt which 20 is mounted for both rotatory and sliding movements, and which is normally projected under the influence of a spring, the spindle being slideable through the door, and the spindle and latch bolt having coöperating 25 means whereby when the spindle is slid properly for opening the door, the latch bolt will be rotated so that it may readily be disengaged from the keeper when the door is pulled or pushed open by the spindle 30 or knobs carried thereby.

It is the object of the invention to provide a door latch of the nature indicated, embodying a novel assemblage of the component parts, whereby the efficiency and utility 35 of the device is enhanced, and in order that the device is comparatively simple and inexpensive in construction, may be readily installed upon a door, and will effectively serve its office.

40 With the foregoing and other objects in view which will appear as the description proceeds, the invention resides in the combination and arrangement of parts and in the details of construction hereinafter described and claimed, it being understood 45 that changes in the precise embodiment of the invention herein disclosed can be made within the scope of what is claimed without departing from the spirit of the invention.

50 The invention is illustrated in the accompanying drawing, wherein:—

Figure 1 is a horizontal section through the device, taken on the line 1—1 of Fig. 2. Fig. 2 is a vertical section taken on the line

2—2 of Fig. 1. Fig. 3 is a vertical section 55 taken on the line 3—3 of Fig. 1.

In carrying out the invention, there is employed a tubular casing 1 which is fitted in a bore or circular mortise 2 drilled in the free edge portion of the door 3, the casing 1 having a reduced inner end portion 4, and having a flange or plate 5 at its outer end or mouth which is adapted to rest against the free edge of the door.

A latch bolt 6 of circular cross section is 65 mounted snugly within the casing 1 for both rotatory and reciprocatory movement, and is provided with a reduced inner end portion 7 projecting into the reduced portion 4 of the casing to coöperate with a coiled wire 70 expansion spring 8 disposed within the said portion 4 of the casing. The spring 8 bears at one end against the inner end of the casing, and a headed bearing member 9 is fitted within the other end of the spring 8 and 75 bears against the pointed end of the end portion 7 of the latch bolt, whereby the latch bolt may turn easily within its casing. The spring 8 tends to project the latch bolt, but notwithstanding this, the latch bolt may 80 turn readily within the casing.

The latch bolt 6 has a reduced outer end portion 10 which passes slidably through an aperture 11 provided in a face plate 12 resting against the flange or plate 5, screws or 85 other securing elements 13 being engaged through the plates 12 and 5 for clamping them against the free edge of the door. The reduced outer end portion 10 of the bolt in passing through the restricted aperture 11 90 will prevent the excessive outward movement of the latch bolt, since the latch bolt will seat against the plate 12 which acts as a stop, the latch bolt 6, however, being readily removable when the plate 12 is removed. 95 The end portion 10 of the latch bolt has an oblique cam face 14 to engage and coöperate with the keeper 15 carried by the jamb 16 of the door frame or casing.

The door 3 is provided with a second bore 100 17^a drilled therethrough from one side to the other adjacent and between the ends of the bore 2, and the spindle 17 extends through the bore 17^a outside of the casing 1 whereby the spindle may be reciprocated 105 from one side to the other. The casing 1 is provided with an opening or cut away portion 18 adjacent the bore 17^a and receiving

the longitudinal rack 18^a carried by the spindle 17. The latch bolt 6 is provided with a gear or toothed portion 19 intermeshing with the rack 18^a, whereby when the spindle is reciprocated, the bolt 6 will be rotated.

As a means for slidably supporting the spindle 17, guide plates or disks 20 are secured by means of screws or other securing elements 21 to the opposite sides of the door 10 and have central instruck tongues 22 providing apertures through which the spindle is slidably snugly, the tongues 22 bearing upon that side of the spindle opposite the rack 18^a in order to hold the rack in proper engagement with the gear 19.

A knob or handle 23 is secured upon one end portion of the spindle, while a similar knob or handle 24 is secured upon the other end portion of the spindle.

20 A plate or disk 25 is secured to one side of the door and has a depression 26 receiving the respective disk 20, the same screws 21 which secure said disk 20 to the door being employed for securing the plate 25 thereto.

25 The plate 25 has an outstanding neck or collar 27 surrounding the spindle, and a sleeve 28 is slipped onto the hub 29 of the knob 24, and is secured thereon by the same screw 30 that is employed for fastening the hub 29

30 upon the spindle. The sleeve 28 fits telescopically or slidably over the neck or collar 27, and the said sleeve and neck provide a housing inclosing a coiled wire expansion spring 31 which surrounds the spindle and

35 which bears against the hub 29 of the knob 24 and the respective disk 20. The spring 31 moves the knobs 23 and 24 toward and away from the door, respectively, when the spindle is released, and which will rotate the

40 latch bolt to normal position, as seen in full lines Fig. 1.

Supposing the door to be opened with the spindle released, the spindle will be moved under the influence of its spring 31 to normal position, as seen in full lines in Fig. 1, and this will rotate and hold the latch bolt

45 at such a position, that it may readily snap into engagement with the keeper 15 when the door is closed. To open the door, either the knob 23 is pulled away from the door, or

50 the knob 24 is pushed toward the door, which will cause the spindle 17 to be slid through the door, and as a consequence, the

latch bolt 6 will be rotated through one-half revolution to reverse the position of the cam 55 face 14. The latch bolt 6 will therefore readily disengage the keeper 15 when the door is forced open, the latch bolt 6 being forced inwardly against the tension of its spring 8.

60 The present invention eliminates the complicated mechanisms usually employed for operating the latch bolt, it being noted that the present device is extremely simple and compact in construction, and requires only 65 the drilling of two bores in the door to accommodate the working parts. The latch device may therefore be readily applied to the door, and is of advantage for various obvious reasons over the ordinary door latch 70 wherein the knobs must be turned for retracting the latch bolt.

75 The latch device is not only of advantage for use on doors, but may also be used advantageously upon drawers, and other movable objects. Any suitable spring means may be employed in lieu of the spring 31 for yieldably moving the spindle in the proper direction.

Having thus described the invention, what 80 is claimed as new is:

In a latch device, a tubular casing having a flange at one end, a latch bolt slidable and rotatable snugly therein, a spring between the inner ends of the latch bolt and casing 85 for projecting the latch bolt, a face plate resting against said flange to serve as a stop for holding the latch bolt within the casing, the face plate having a restricted aperture, and the outer end of the latch bolt being reduced and projecting through said aperture, the outer end of the latch bolt having a cam 90 to engage a keeper, the latch bolt having a gear, and a slideable spindle outside of the casing having a rack engaging said gear 95 whereby when the spindle is slid, the latch bolt is rotated from one position to another, the casing having an opening receiving the rack.

100 In testimony that I claim the foregoing as my own, I have hereto affixed my signature in the presence of two witnesses.

MARION ALLEN RADER.
